(57) **CLAIM**

An ornamental design for a house shaped pastry, as shown and described.

DESCRIPTION

FIG. 1 is a front elevation view of the front component of a house shaped pastry, the rear elevation view of the rear component being a mirror image thereof;

FIG. 2 is a perspective view of the front component, the perspective view of the rear component being identical thereto;

FIG. 3 is a right side elevation view of a right component of the house shaped pastry, the left side elevation view of the left component being identical thereto;

FIG. 4 is a perspective view of the right component of FIG. 3, the perspective view of the left component being identical thereto;

FIG. 5 is a top plan view of a top component of the house shaped pastry;

FIG. 6 is a perspective view of the top component of FIG. 5;

FIG. 7 is a front elevation view of the assembled house shaped pastry;

FIG. 8 is a right side elevation view thereof, the left side elevation view being identical thereto;

FIG. 9 is a top plan view thereof; and,

FIG. 10 is a front, top, right side perspective view thereof.

1 Claim, 6 Drawing Sheets
